UNITED STATES PATENT OFFICE

152,525

DESIGN FOR A KNIFE OR SIMILAR ARTICLE OF FLATWARE

Harry K. Friedman, New York, N. Y.

Application August 13, 1947, Serial No. 140,843

Term of patent 3½ years

(Cl. D54—12)

To all whom it may concern:

Be it known that I, Harry K. Friedman, a citizen of the United States, residing at New York, in the county of Queens and State of New York, have invented a new, original, and ornamental Design for a Knife or Similar Article of Flatware, of which the following is a specification, reference being had to the accompanying drawings, forming a part thereof.

In the drawings:

Fig. 1 is a side elevational view of a knife showing my new design, the opposite side presenting substantially the same appearance as the side shown, and

Fig. 2 is a top plan view of the same.

The essential features of my design reside in the handle portion of the knife shown in full lines.

I claim:

The ornamental design for a knife or similar article of flatware, substantially as shown and described.

HARRY K. FRIEDMAN.
